DESIGN FOR A COMBINATION CIGARETTE CONTAINER AND DISPENSER

Judson Craig Eubank, New York, N. Y.

Application December 5, 1944, Serial No. 116,714

Term of patent 7 years

(Cl. D85—2)

To all whom it may concern:

Be it known that I, Judson Craig Eubank, a citizen of the United States, residing at New York, in the county of New York and State of New York, have invented a new, original, and ornamental Design for a Combination Cigarette Container and Dispenser, of which the following is a specification, reference being had to the accompanying drawing, forming part thereof:

Fig. 1 is a perspective view, showing my new design of a combination cigarette container and dispenser, and

Fig. 2 is a front elevational view thereof.

I claim:

The ornamental design for a combination cigarette container and dispenser, substantially as shown.

JUDSON CRAIG EUBANK.
